UNITED STATES PATENT OFFICE.

HENRY L. KIRKPATRICK, OF PHILADELPHIA, PENNSYLVANIA.

ADDING DEVICE.

1,180,930.

Specification of Letters Patent.

Patented Apr. 25, 1916.

Application filed September 18, 1914. Serial No. 862,262.

To all whom it may concern:

Be it known that I, HENRY L. KIRKPATRICK, a citizen of the United States, residing in the city and county of Philadelphia, State of Pennsylvania, have invented a new and useful Adding Device, of which the following is a specification.

My invention consists of a device for adding figures, which is portable and adapted to be carried in a pocket and capable of counting and adding sums of small numbers.

It further consists of such a device in which an index is provided for indicating the number of the maximum sums counted on the dials of the device.

It further consists of other novel features of construction, all as will be hereinafter fully set forth.

20 The annexed drawing and the following description set forth in detail one mechanical form embodying the invention, such detail construction being but one of various mechanical forms in which the principle of 25 the invention may be had.

In said annexed drawings—Figure 1 represents an elevation of the device. Fig. 2 represents an axial section of the same. Fig. 3 represents a plan view of the unit counting dial. Fig. 4 represents a plan view of the decimal counting dial-disk. Fig. 5 represents a plan view of the back of such dial-disk. Fig. 6 represents a plan view of the inner side of the back-casing.

35 Similar numerals of reference indicate corresponding parts in the figures.

Referring to the drawings, the reference numeral 1 indicates a circular disk having the numerals from "1" to "9" marked equidistantly in a circle and having an opening, 2, at the point where the cipher would be in a division of the disk in ten equal divisions. A circular back-casing, 3, has an annular side-flange, 4, and has its bottom raised to 45 form an annular groove, 5, at said flange. A tongue, 6, projects from the edge of the front dial-disk and is doubled upon itself and has its end bent at a right angle to fit into a loop, 7, upon the side-flange of the 50 back-casing, whereby the front disk and back-casing are connected. A sleeve, 8, extends from the center of the bottom of the

back-casing and has its end upset over the edge of a central opening in the front dial-disk, at 9, to secure said disk upon said sleeve. An annular unit-counting dial, 10, has an annular flange upon its inner edge, which flange fits to rotate in the annular side-flange of the back-casing, and said annular dial has on its periphery teeth or projections, 11, in the present instance ten in number. The annular dial has the cipher and digits marked upon its outer face at equal distances from each other, so that such figures may be successively presented 60 through the opening in the face plate 1, and said figures register with the teeth, so that each figure applies to one tooth. A decimal dial, 12, is journaled with its center upon the central sleeve and has the cipher and 65 nine digits marked in an annular series upon its outer face at equal distances and to register with the opening in the front disk. The raised center, 13, of a ratchet disk, 14, is journaled at its center upon the sleeve and 70 secured to or forming a part of the decimal dial 12, and said ratchet disk has ratchet teeth, 15, on its periphery, each tooth registering with one of the figures of the decimal dial. A flat and inwardly bent spring, 16, 75 is secured upon the inner periphery of the annular dial with its free end registering with one figure upon the face of the same, preferably with the cipher mark, and the free end of said spring engages the ratchet- 80 teeth of the decimal dial structure. The raised center of the back-casing has a straight portion, 17, in its edge, and the spring-pawl of the annular unit dial bears against the periphery of such center to be 85 held out of engagement with the ratchet-teeth of the decimal dial, but will spring inward to engage a tooth of said dial when it arrives at the straight cut-away portion, to engage and move the decimal dial for the 90 space of one tooth at each revolution of the annular dial. A screw, 18, is journaled in the central sleeve of the back-casing, and has a knob, 19, at one end bearing against the back-casing, and a thread, 20, upon which 100 an index-hand, 21, is secured by a nut, 22, which hand can be turned to point to one of the numerals upon the front disk to indicate the hundreds, each time one-hundred

has been counted upon the dials and two ciphers are exposed at the opening in the front disk.

In practice, the annular dial is rotated by engaging the teeth of the same until the two ciphers of the disks show through the opening in the front dial disk. When beginning to count, the projection upon the annular dial opposite the number on the face dial which is to be counted is turned until it engages beneath the ear of the face disk. This will expose the figure counted through the opening of the face disk. The projection corresponding to the next number to be counted is then turned to the ear upon the face disk, and so forth until the numbers are all added. Each time the annular dial makes one revolution and counts ten, the decimal dial is moved one tooth and the space of one numeral, the two numerals exposed through the opening in the face-dial indicating the total counted. When the numerals showing through the opening in the face disk are the two ciphers, the amount counted is one hundred, and the device begins on the next hundred, and to register the hundred the hand is pointed to the number on the face plate indicating the number of the hundred just counted. The device will thus add up to and register one thousand.

The device is very simple of construction and consists of comparatively few parts, so that the device is durable and inexpensive to construct, and is not liable to get out of order.

Other modes of applying the principle of my invention may be employed for the mode herein explained. Change may therefore be made as regards the mechanism thus disclosed, provided the principles of construction set forth, respectively, in the following claims are employed.

Having thus described my invention, what I claim as new and desire to secure by Letters Patent, is:—

1. In a device of the character stated, a face dial having an annular series of numerals and an opening, an annular dial revolvably supported beneath said face dial to have a series of numerals upon its face successively register with said opening and having peripheral projections registering with the numerals upon it and upon the face-dial, a dial revolvably supported beneath the face dial and within the annular dial and provided with a raised central ratchet portion and having an annular series of numerals adapted to successively register with the opening in the face-dial, co-operating peripheral means for holding said face dial and the back of the device together, and means for rotating said last dial for the space of one numeral for one whole revolution of said annular dial.
2. In a device of the character stated, a

face dial having an annular series of numerals and an opening, an annular dial revolvably supported beneath said face-dial to have a series of numerals upon its face successively register with said opening and having peripheral projections registering with the numerals upon it and upon the face-dial, a dial revolvably supported beneath the face-dial, and within the annular dial and having an annular series of numerals adapted to successively register with the opening in the face-dial and peripheral ratchet teeth registering with said numerals, and a flat and inwardly bent spring upon the annular dial and its free end adapted to engage directly one of such ratchet-teeth once at each revolution.

3. In a device of the character stated, a face dial having an annular series of numerals and an opening, a back casing having an annular side-wall and an annular groove in its bottom, said back casing having a raised center having a straight portion in a portion of its inner face and a central sleeve having its end secured in the center of the face-dial, an annular dial having a flange on its inner periphery and within the side-wall of the back-casing and having an annular series of numerals successively registering with the opening in the face-dial and peripheral projections registering with such numerals, a dial having an annular series of numerals registering with the opening in the face-dial and rotatably supported upon the central sleeve and provided with ratchet teeth registering with the numerals upon it, interengaging peripheral means on the face dial and the back casing for connecting the same, and a spring pawl upon the inner periphery of the flange of the annular dial rotating in the groove of the back and engaging a tooth of the inner dial when passing the straight portion of the side of the annular groove.

4. In a device of the character stated, a casing having an annular side flange and raised bottom forming an annular groove at said flange, a face dial having an annular series of numerals and an opening, dials rotatable within said casing and having numerals successively presenting at the opening in said face dial and having peripheral projections registering with the numerals of the face dial, one of said dials having peripheral ratchet teeth registering with said numerals, and a spring pawl located in said groove and mounted to engage one of such ratchet teeth once at each revolution, one of said dials having a flange projecting into said groove, said back casing having a sleeve passing through said dials and serving to secure the face dial in position.

5. In a device of the character stated, a back casing having an annular side flange and raised bottom forming an annular groove at said flange, a face dial, dials rota-

table within said casing, one of said dials having a flange projecting into said groove, said back casing having a sleeve passed through said dial and serving to secure the 5 face dial in position, and a screw mounted in said sleeve having a knob at one end bearing against the back casing and an index

hand on the other end movable over the front dial.
